United States Patent Office

Des. 191,274
Patented Sept. 5, 1961

191,274

SWING SEAT

Ralph E. Williams and Warren P. Miller, Anderson,
Ind., assignors to American Playground Device Co.,
Anderson, Ind., a corporation of Indiana

Filed June 15, 1960, Ser. No. 60,971

Term of patent 14 years

(Cl. D34—5)

FIG. 1

FIG. 2

FIG. 3

FIG. 4

FIG. 5

FIG. 6

FIG. 1 is a top plan view of a swing seat, showing our design;

FIG. 2 is a front elevational view of the same;

FIG. 3 is a vertical section taken approximately along line 3—3 of FIG. 2 on an enlarged scale and looking in the direction of the arrows;

FIG. 4 is an end elevational view of the swing seat;

FIG. 5 is an enlarged perspective view of the swing seat; and

FIG. 6 is a bottom plan view of the same.

We claim:

The ornamental design for the swing seat, as shown.
